(57) **CLAIM**

The ornamental design for a display screen, or portion thereof, with an animated graphical user interface, as shown and described.

DESCRIPTION

FIG. 1 is a front view of an embodiment of a display screen, or portion thereof, with an animated graphical user interface showing a first image of the claimed design;

FIG. 2 is a second image thereof;

FIG. 3 is third image thereof;

FIG. 4 is a fourth image thereof;

FIG. 5 is a fifth image thereof;

FIG. 6 is a sixth image thereof;

FIG. 7 is a seventh image thereof; and

FIG. 8 is an eighth image thereof.

FIG. 9 is a front view of another embodiment of a display screen, or portion thereof, with an animated graphical user interface showing a first image of the claimed design;

FIG. 10 is a second image thereof;

FIG. 11 is third image thereof;

FIG. 12 is a fourth image thereof;

FIG. 13 is a fifth image thereof;

FIG. 14 is a sixth image thereof;

FIG. 15 is a seventh image thereof; and

FIG. 16 is an eighth image thereof.

FIG. 17 is a front view of another embodiment of a display screen, or portion thereof, with an animated graphical user interface showing a first image of the claimed design;

FIG. 18 is a second image thereof; and

FIG. 19 is third image thereof.

FIG. 20 is a front view of another embodiment of a display screen, or portion thereof, with an animated graphical user interface showing a first image of the claimed design;

FIG. 21 is a second image thereof; and,

FIG. 22 is a third image thereof.

The outer broken lines in the figures show a display screen, or portion thereof, and form no part of the claimed design.

(Continued)

The other broken lines in the figures show portions of the animated graphical user interface that form no part of the claimed design.

The appearance of the animated graphical user interface transitions between the images shown in FIGS. 1-8, between the images shown in FIGS. 9-16, between the images shown in FIGS. 17-19, and between the images shown in FIGS. 20-22.
